[57] CLAIM

The ornamental design for a combined cane and toilet paper holder, as shown and described.

DESCRIPTION

FIG. 1 is a perspective view of a combined cane and toilet paper holder showing my new design;

FIG. 2 is a right side elevational view;

FIG. 3 is a rear elevational view;

FIG. 4 is a top plan view; and

FIG. 5 is a bottom plan view.

The broken line showing of a toilet paper roll in FIGS. 1 and 2 is for illustrative purposes only and forms no part of the claimed design.
